UNITED STATES PATENT OFFICE.

RICHARD B. ROBBINS, OF ADRIAN, MICHIGAN.

CULTIVATOR.

SPECIFICATION forming part of Letters Patent No. 242,478, dated June 7, 1881.

Application filed March 29, 1880. (Model.)

To all whom it may concern:

Be it known that I, R. B. ROBBINS, a citizen of the United States, residing at Adrian, in the county of Lenawee and State of Michigan, 5 have invented certain new and useful Improvements in Cultivators; and I do hereby declare the following to be a full, clear, and exact description of the invention, such as will enable others skilled in the art to which it appertains 10 to make and use the same, reference being had to the accompanying drawings, and to letters or figures of reference marked thereon, which form a part of this specification, in which—

Figure 1 is a side elevation of the machine; 15 Fig. 2, a plan view; Fig. 3, a perspective of one rail, hand-lever, and adjusting devices, one of the wheels removed, and portions of the machine broken away; Fig. 4, a perspective of one rail, showing the manner of attaching standard- 20 iron thereto; Fig. 5, a side view of rail, and standard affixed thereto, and shovel, the shovel and its connection to standard being in vertical section. It is also a rear view of the shovel, showing the notched sleeve secured thereto, 25 and a separate view of the loose sleeve, through which the standard passes; and Fig. 6 is a perspective of both tongue and neck-yoke clevis, showing the mode of connecting the two together.

30 My invention relates to wheel-cultivators, but it is also applicable to harrows, gang-plows, potato-diggers, planters, and other similar implements designed either for tilling the soil, planting, or harvesting root-crops; and it consists in the construction and in the combination of parts hereinafter particularly described.

In the drawings, the letter A indicates the tongue, composed of two poles secured to the cross-bar B, and strengthened by the braces a 40 bolted to the poles and the cross-bar B, whereby any uneven strain is prevented from working the parts loose.

To each end of the cross-bar B there are bolted or otherwise secured angle-irons C, 45 formed with the lower horizontally-projecting spindles, c, upon which the wheels D are journaled.

On the end of the tongue there is placed an iron, E, for the purpose of holding the two 50 parts secure, and which is provided with a pin, d, at the front end, on which is formed a bit or lug, e.

In the rear part of the neck-yoke clevis F there is formed an eye-slot, f, which is large enough and extends far enough back to permit the pin and lug on iron E to pass therein to a groove formed at the rear end thereof, so that when the neck-yoke is placed in position upside down and given a half-turn it is securely locked, thus preventing the up-and-down motion of the neck-yoke on the tongue, and at the same time securing a free lateral or horizontal movement of said neck-yoke.

To each pole of the tongue there is bolted or otherwise secured an iron pendant, G, braced 65 by iron H bolted to the tongue, and secured and held in position by nut g on the lower end of the pendant G.

Upon the lower part of the pendant G there is placed an iron sleeve, I, which has a free up-and-down or perpendicular movement on the pendant. The lower portion of the sleeve I is formed with an extension, J, to which the rails of the cultivator are attached.

To the upper end of the extension J there is 75 fastened the swivel-link K, which connects the sleeve I and the hand-lever L, hereinafter described.

The seat M and seat-bars N are constructed and fastened to the poles of the tongue in the 80 usual manner.

The hand-lever L is provided with a suitable fulcrum, O, on the pole of the tongue A, and is connected to the sleeve I by the swivel-link K.

The graduating-rack P is bolted to the cross-bar D, as indicated, and is provided with an L-flange, Q, which, in connection with rack P, forms suitable bearings, on which is journaled a friction-roller, h, on which rests the short lever R, which is pivoted at one end to the hand-lever L.

To the free end of the short lever there is secured a chain, S, the other end of which is fastened to the rear end of rail T, as shown.

On the rear part of the hand or main lever L 95 there is placed a locking device, composed of the rod U, spring i, and handle V, as shown. The rod U slides in guides j, which hold it to the hand-lever, and the spring i, which is coiled around the rod, fits between a shoulder formed thereon and one of the guides j, and presses the rod forward, so as to keep one end of it in contact with the ratchet-edge of the rack P. The other end of the rod is joined to the handle 100.

V, as clearly indicated in Figs. 1 and 3, and the handle is hinged to the hand-lever, so that when it is pressed in next to the hand-lever it will draw back the rod from contact with 5 rack P.

By uniting the front and rear ends of the hand-levers, as indicated and described, with the front and rear ends of the cultivator-rails T, I am enabled at all times to keep the 10 cultivator level when in the ground. Instead of using the short lever R, I may use a pulley on top of the rack P, and extend the lifting-chain S over it and unite it to the main lever L. These short levers R are shown projecting 15 to the rear, but they may be reversed if desired.

The front lever, W, is fastened to the locking-rod U by means of a pin, k, projecting from the rod and passing through the top of the foot-lever, and is further pivoted, below that point, to a flange, X, depending from the under side of the hand-lever, and is limited in its movement and at the same time braced by the staple l passing over it and into the hand-lever. By 25 thus attaching the foot-lever to the locking-bolt the operator is enabled to raise and lower the cultivator-rails with his foot at will, as by placing his foot upon the lever W and pressing forward it draws the locking-rod U from 30 the rack P, and leaves the hand-lever L free to move up and down, as may be desired.

The parts of the machine as thus constructed and described may be used by detaching the rails T and substituting a harrow, gang-plow, or any other similar implement designed either for stirring the soil, planting, or harvesting root-crops. As shown in Figs. 1, 2, 35 and 3, the machine is designed for cultivating corn and other crops planted in rows, to which shields and whiffletrees may be attached in the usual manner. In order to convert it into a field or fallow cultivator, I place between the rails T one or more center rails with shovels attached.

45 The standard-iron Y (shown in Fig. 4) is constructed so that its two parts will be at right angles to each other and one part, m, will bear across the bottom of the rail, and the other, n, along the side of the rail. The iron is secured 50 to the rail by one bolt passed vertically through the rail and one part of the iron, and another passed transversely through rail and iron, as illustrated in Fig. 4, and when so secured the part n of the iron stands at an oblique angle 55 to the length of the rail. By bolting the standard-iron to the bottom and side of the rail, instead of the top and side, I am enabled to afford a brace to resist any lateral pressure on the standard which is pivoted to the iron at its 60 elbow, and by passing the bolts through both iron and rail, as described, the rail is much less liable to split.

The standard Z is made of the form shown in Fig. 5, the upper end being slotted, as shown, 65 and the lower part beveled to form a wedge, as illustrated, and made to terminate below the

wedge in a rounded end, which is threaded. The standard is secured to the iron Y at its elbow by a bolt passed through both, on which bolt the standard is free to turn, and it is further secured to the iron at the top by a friction-bolt, o, passed through it and the slot in the upper end of the standard. By means of the bolt o and the nut thereon, and the slot in the standard, the standard, and through it the tooth or shovel, is adjusted to the pitch desired. 70

The upper end of the standard, along the slot therein, is beveled, so that when the shovel comes in contact with any obstruction the friction nut or bolt o will let loose much quicker than it would if the standard were made in the usual form. 80

The lower part of the standard, where it passes through the sleeve A', is made wedge 85 shape, and the extreme lower part, p, is rounded and threaded. The loose sleeve A' is made so as to slip up over the wedge of the standard, and has a lug, q, formed on its lower face, which is designed to engage with any one of the slots 90 made in the sleeve B', formed on the back of the shovel C'. 95

The sleeve B', which is cast with or bolted to the rear of shovel C', has a hole passing centrally through it, and is provided with slots 1, 2, and 3 at both top and bottom, so as to enable me to reverse the tooth or shovel when desired. These slots, in combination with the lug q on loose sleeve A', when the shovel is placed on the standard z, enable me to fasten the shovel 100 with its face to the front, or so as to throw the dirt either to the right or left, as may be desired.

The tooth or shovel C' is formed with a cutting-edge at each end, with one end much wider than the other, thus combining the ordinary bull-tongue with a common or ordinary cultivator-shovel. By this combination I virtually secure two machines in one by simply reversing the ends of the shovels, and this 105 is not only a great convenience, but a great saving of expense. In cultivating corn when it is small and only necessary to stir the top of the soil I use the small point or bull-tongue; but later in the season, when the grain is larger, 110 I reverse the shovel and cut the ground thoroughly. Also, in summer-fallow, when it is desirable to stir the entire surface, I use the broad cut; but in cultivating in wheat or other small grain, when it is only necessary to cover 115 the same, it can be done much more effectively by having the broad point up, as by so using it the dirt is thrown so as to more completely cover the grain, and leave it more evenly distributed on the ground. 120

I am aware that levers, friction-balls, plow-standard pendants, and reversible teeth have been used in cultivators. I do not therefore claim any of these points, broadly; but

What I do claim, and desire to secure by Letters Patent, is—

1. The lever R and chain S, in combination

- with beam T, lever L, rack P, and roller h, substantially as set forth.
2. The foot-lever W, in combination with lever L, rack P, and locking-bolt U, as described.
- 5 3. The lever L, provided with sliding rod U, and operating-spring, in combination with rack P, lever V, and foot-lever W, the several parts operating as described.
- 10 4. The reversible shovel C', constructed with one end wider than the other, and provided with sleeve B', slotted as described, for the purposes set forth.
- 15 5. The standard Z, in combination with sleeve A', provided with lug g, and a shovel or tooth provided with sleeve B', slotted as described, for the purpose set forth.
- 20 6. The standard-iron Y, constructed as described and secured to the bottom and the side of the rail, in combination with the plow-standard, substantially as described.
7. The combination of a cultivator-beam, standard-iron Y, constructed and secured to the beam as described, and the standard Z, slotted and beveled along the slot and secured 25 to said iron, as described, for the purpose set forth.
8. The sleeve B', provided with one or more slots at both top and bottom, in combination with a double-pointed shovel, for the purposes 30 set forth.
9. The sleeve A', provided with lug q, in combination with the standard Z and sleeve B, slotted at one or both ends, substantially as described.
- 35 In testimony whereof I affix my signature in presence of two witnesses.
